UNITED STATES PATENT OFFICE.

DANIEL J. RYAN, OF CLEVELAND, OHIO, ASSIGNOR TO THE CLEVELAND TRUST COMPANY, OF CLEVELAND, OHIO, A CORPORATION OF OHIO.

MOLD.

Application filed April 17, 1925. Serial No. 23,813.

The invention relates to improvements in semi-permanent molds of the character disclosed in my pending application Serial No. 538,457, and which are especially adapted 5 for the casting of aluminum alloy or equivalent metal pistons or other cup-shaped articles.

The objects of the present invention include simplifying the construction, reducing 10 the cost of production and rendering easier the operation of molds of the character in question.

A further object of the invention is to produce a mold of the character in question that 15 requires only a moderate amount of skill and training on the part of the operator in order to produce castings of uniformly high quality.

Other objects more or less ancillary to the 20 foregoing as well as the manner of attaining all of the various objects will appear in the following description of the preferred embodiment of the invention illustrated in the drawings.

25 In the drawings, Fig. 1 is a side elevation of my improved mold.

Fig. 2 is an end elevation of the same.

Fig. 3 is an enlarged sectional elevation, 30 the section being taken on the line 3—3, Fig. 1. Fig. 4 is a section on the line 4—4, Fig. 1.

Fig. 5 is an enlarged plan view of the casting formed in the mold before the gate metal is detached.

Fig. 6 is a side elevation of the casting 35 shown in Fig. 5.

Fig. 7 is an enlarged fragmentary section on the line 7—7, Fig. 3.

Referring in detail to the construction 40 illustrated, the body of the mold consists essentially of two side members or halves 1 and 2. The adjacent or abutting faces of the mold halves are formed with registering recesses to provide a casting cavity 3 and a gate cavity designated in its entirety by 4 and 45 comprising a pouring section 5 and an upright in-gate section 6. The mold halves are fitted with upright extensions 7 and 8 which are recessed to form the upper parts of the pouring section 5 and the in-gate section 6 50 of the gate. These upper parts of the gate extend well above the top of the mold cavity as is clearly indicated in Fig. 3. The extensions 7, 8 have the upper end of their cavity flared at 7^a to afford a suitable pouring 55 mouth for the gate. The in-gate section 6 of

the gate communicates with the casting cavity of the mold from the bottom thereof to substantially the top thereof through a narrow passage 9 (Figs. 4 and 7). Preferably, however, this passage 9 is somewhat wider 60 near the bottom, as is indicated in Fig. 3 and by the casting as shown in Fig. 6. It will be noted that the pouring section 5 of the gate extends downward and laterally and thence upwardly, after the manner of the 65 well-known horn gate, into the bottom of the in-gate cavity 6.

The bottom wall of the casting cavity of the mold is formed by an upstanding cylindrical block 10 (Fig. 3). The block 10 is 70 mounted on a cross plate 11 which in turn is carried by any suitable support such as the frame 12, made of steel angles or other suitable forms bolted or riveted together. The block 10 is preferably formed with a central 75 depression 10^a to provide a turning boss on the head of the piston casting.

The core of the mold as shown is formed of reinforced green sand and is of the same character as the core described in my companion application Serial No. 23,812, to which reference may be had for a detailed description of the preferred method of making the core. The core, which is designated in its entirety by 13, comprises the main body 80 part 14 of fine green molding sand and a reinforcing structure which consists of a circular and preferably annular core print section 15 formed with an integral cross bar 15^a, and a section completely embedded in the sand consisting of a rod or stem 16 which has its upper 85 threaded end secured in an aperture in the cross bar 15^a by means of a wing nut 17. The lower end of the stem 16 is split, preferably into quarters 16^a which are opened up or 90 spread apart as clearly indicated in Fig. 3. Preferably these spreading branches or fingers 16^a in addition to their inward taper are additionally tapered radially toward 95 their lower ends as best shown in Fig. 3. 100

The core print section 15 of the core is designed to rest upon the top surfaces of the mold halves adjacent the mouth of the casting cavity and is definitely and accurately located relative to the casting cavity by diametrically opposite notches 15^b, 15^b, which engage with correspondingly shaped lugs 18 on the mold halves. The sand body of the core is preferably provided with a number of 105 vertically extending vent passages 14^a to fa- 110

cilitate free escape of vapors and gases through the core body when the molten metal enters the mold.

19 is a heavy weight designed to be placed 5 on the top of the core print 15 after the core has been inserted in the mold and serves to hold the core down against the buoyant effect of the entering molten metal. A standard 20 is provided as a convenient means for supporting the weight 19 when the latter is not 10 in use.

The mold halves 1 and 2, their upward extensions 7 and 8, and the cylindrical block 10 are preferably formed of cast iron which 15 can readily be machined and worked to the desired forms. The mold halves 1 and 2 are preferably formed with top and bottom flanges 1^a, 1^b and 2^a, 2^b, and also with vertical strengthening ribs 1^c, 2^c. In the preferred 20 construction illustrated the mold halves are slidably mounted on the supporting frame and mechanism is provided for moving the two halves from and toward each other. On the two ends of the main supporting frame 25 12 are mounted rectangular frame castings 21 and 22 and these end castings are connected by a pair of round top bars 23, 23 and a similar pair of bottom bars 24, 24. The mold halves are formed with apertures through 30 which these two sets of bars pass as shown in Figs. 1 and 3 and said mold halves are thus slidably supported on the bars. To open and close the mold a pair of shafts 25, 26 are 35 rotatably mounted in the frame 21 and geared together by pinions 27, 27 fast thereon. The upper shaft 25 is fitted at one end with an actuating lever 28 and both shafts are fitted at both ends with crank arms 29, 29. These crank arms are in turn connected 40 by links 30, 30 with the mold half 1. Similarly shafts 31, 32 having intermeshing pinions 33, 33, are mounted in the frame 22 and are connected at their ends by means of cranks 34, 34 and links 35, 35 with the other 45 mold half 2. The shaft 31 is fitted with a hand lever 36 to actuate the shafts 31 and 32. I prefer to make one of the sets of links adjustable in length and in the construction shown the links 30 are so made.

50 With the mechanism described the mold halves can be opened and closed very easily and very quickly by simply swinging the crank arms 28 and 36. Obviously the mold parts should be of such forms and sizes that 55 the mold halves will simultaneously come into mutual engagement with each other and with the sides of the cylindrical block 10. Alignment of the parts can readily be effected by adjusting the block 10 for engagement 60 with the mold half 2 and then the links 30 can be adjusted to insure contact of the faces of the mold half 1 with the mold half 2 and the block 10, it being understood that a slight amount of play is provided between the mold

halves and the guide bars 23, 24 upon which 65 they are supported.

In utilizing the mold for making piston castings I prefer to core out the wrist pin bosses. For this purpose I slidably mount a pair of core pins 37, 38 in the mold halves 70 1 and 2 respectively. These pins are provided with handles 37^a, 38^a which can be conveniently grasped by the operator to withdraw the pins from engagement with the casting as soon as the metal freezes following 75 the pouring.

The metal-reinforced green sand core above described can be made in various ways. In my pending application Serial No. 538,457, I have described a method of making such cores by hand and in my companion application Serial No. 23,812, I have disclosed another method of making cores of this character in which the metal reinforced structure is mounted in the core box and then the sand is introduced by blowing with compressed air. I prefer to employ the latter method because of the great speed and economy with which the cores can be made. I will not here describe the latter method in 90 detail because reference can be had to my said application Serial No. 23,812, for a detailed description thereof, and for the further reason that it is obvious that the present invention is not dependent on the method 95 of forming the core and that the core can, if desired, be made by hand. In the latter case it is only necessary to mount the assembled core reinforcing structure in the core box, the core print structure 15 resting upon the top of the core box adjacent the cavity thereof and the stem 16 depending into said cavity, upstanding guide means being provided on the core box to engage the notches 15^b of the core print so that it is accurately 100 positioned in relation to the core box cavity. Then the green sand can be introduced by hand through the core print to fill the core box. Next the vent passages 14^a can be 105 formed by forcing a wire or slender rod down into the core in the well known manner. This having been done, the core box can be inverted and the parts of the box separated to free the core. In introducing the sand the downwardly tapering form of the finger 16^a facilitates the solid formation of the sand core around the reinforcing structure, it having been found that it is more difficult to introduce the sand solidly around said structure where the tapering formation is not employed. This is particularly important too, 110 when the sand cores are blown by compressed air.

In the use of my improved mold, the mold operator first closes the mold by swinging the lever arms 28 and 36 thus bringing the mold halves 1 and 2 into engagement with each other and with the cylindrical block 10. 125

He then places the core in position in the mold cavity with the notches of the core print engaging the guides 18 so as to accurately position the core in the mold cavity. The heavy weight 19 is then lifted from its standard 20 and placed upon the core print as indicated in Fig. 3 so as to hold the core firmly in position. Next the core pins 37 and 38 are pushed in to their positions indicated in Fig. 4. Thereupon the mold operator with a suitable pouring ladle dips the molten metal such as aluminum alloy from the heated holding pot and pours the metal into the pouring passage 5 of the mold. The molten metal moves through this passage 5 upward into the bottom of the in-gate cavity 6 of the gate and from this cavity flows gently into the casting cavity or matrix of the mold. The pouring is continued until the metal rises to the open top of the in-gate cavity 6, the slight head of metal in said cavity and in the pouring passage 5 serving to insure complete filling of the casting cavity proper.

By conducting the metal through the horn shape pouring passage 5 into the bottom of the in-gate cavity 6 and thence laterally into the casting cavity proper a gentle flow of the metal is insured and attrition of the sand core which might otherwise occur is obviated. As the molten metal enters and slowly rises in the mold cavity there is ample freedom for the escape of air, vapors and gases both through the porous body of the sand core and also upward through the open top of the in-gate cavity 6. Consequently porous castings due to occluded air or gases are entirely avoided. As soon as the initial solidification of the poured metal occurs, as indicated by the shrinkage of the metal in the gate, the operator withdraws the core pins 37, 38. Then, after a sufficient further period to insure thorough setting of the metal of the casting, the mold operator separates the mold sections by swinging one or both of the hand levers 28, 36 whereupon the casting which is still supported upon the cylindrical block 10, can be lifted from the mold. The green sand core is then readily broken out of the casting, whereupon the reinforcing structure comprises the metal core print and its depending branched rod becomes available again for use by the core maker.

It will, of course, be understood that the forms and dimensions of the core and mold body cavity can be varied to produce pistons or other cup-shaped castings of a wide variety of forms. Of course the individual piston casting shown in Figs. 5 and 6 is to be separated from the gate metal by breaking or by means of a saw or other suitable cutting tool; Figs. 5 and 6 show the casting just as it comes from the mold with the gate metal still attached.

Castings made in my improved mold have all of the desirable qualities and characteris-

tics of those described in my copending application Serial No. 538,457. Furthermore the mold of my present invention has the advantages of comparatively light weight, ease and rapidity of operation. The metal parts of the mold are capable of being produced at moderate first cost and the cost of upkeep of the mold is low. In addition, the form of reinforced core employed being adapted to be made of green molding sand by the economic compressed air blowing process set forth in my companion application Serial No. 23,812, further increases the economy incident to the use of my improved mold.

It is to be understood that while I have shown the reinforced sand core suspended in the mold cavity from above by the metal core print, the invention in some of its aspects is not limited to such arrangement, it being possible to arrange the core in other positions so long as it is supported from the mold body by the metal core print, and particularly it is obvious that the core and the mold cavity can be inverted so that the core print supports the core from below. It will also be understood that the construction and arrangement of parts illustrated can be modified in various other respects without departing from the invention as defined in the appended claims.

What I claim is:

1. In apparatus for forming cup-shape castings, the combination of a metal mold body having an open-topped cavity and a pouring gate leading into said cavity; and a core disposed in said cavity so as to form the cup shape matrix of the mold, said core comprising a body of green sand and a metallic reinforcing structure having a stem with downwardly extending branches embedded in the sand body and an annular core print rigid with said stem and engaging the mold body adjacent the mouth of its cavity to sustain and position the core.

2. In apparatus for forming cup-shape castings, the combination of a metal mold body having an open-topped cavity and a pouring gate leading into said cavity; and a core disposed in said cavity so as to form the cup shape matrix of the mold, said core comprising a body of green sand and a metallic reinforcing structure having a stem with downwardly tapering branches embedded in the sand body and an annular core print rigid with said stem and engaging the mold body adjacent the mouth of its cavity to sustain and position the core.

3. In apparatus for forming cup-shape castings, the combination of a metal mold body having an open-topped cavity and a pouring gate leading into said cavity; and a core disposed in said cavity so as to form the cup shape matrix of the mold, said core comprising a body of green sand that forms the inner bottom and side walls and the annular top wall of said matrix and a metal reinforc-

ing structure having a section embedded in the sand and circular core print section rigid with the embedded section and engaging the mold body adjacent the mouth of its cavity to 5 sustain and position the core.

4. In apparatus for forming cup-shape castings, the combination of a metal mold body having an open-topped cavity and a pouring gate leading into said cavity; and a 10 core disposed in said cavity so as to form the cup shape matrix of the mold, said core comprising a body of green sand and a rigid metallic reinforcing structure having a section embedded in the sand and circular core 15 print section engaging the mold body adjacent the mouth of its cavity; and a movable weight formed to engage the said core print section and adapted by gravity to hold the core down against the buoyant action of the 20 molten metal.

5. In apparatus for forming chambered castings, with cylindrical sides the combination of a pair of metal mold halves having in their adjacent faces mating recesses to form 25 the side walls of the mold cavity and additional mating recesses to form a pouring gate leading into said cavity; means for slidably supporting said mold halves for movement toward and away from each other; an up- standing metal cylinder supported at its

lower end, said cylinder being shaped to fit within the lower parts of said recesses and form the bottom wall of the mold cavity; and a core structure disposed in the mold cavity to complete the matrix for the casting. 35

6. In apparatus for forming chambered castings with cylindrical sides the combination of a pair of metal mold halves having in their adjacent faces mating recesses to form the side walls of the mold cavity and additional mating recesses to form a pouring gate leading into said cavity; said gate comprising an upright in-gate section adjacent the mold cavity and in lateral communication therewith and a pouring section extending 40 downwardly, laterally and upwardly into the bottom of the in-gate section; means for slidably supporting said mold halves for movement toward and away from each other; an upstanding metal cylinder supported at its 45 lower end and normally fixed in relation to said supporting means, said cylinder being shaped to fit within the lower parts of said recesses and form the bottom wall of said cavity; and a core structure disposed in the 50 mold cavity to complete the matrix for the casting.

In testimony whereof, I hereunto affix my signature.

DANIEL J. RYAN.
